UNITED STATES PATENT OFFICE.

FREDERICK GILBERT MITCHELL, OF HYDE PARK, LONDON, ENGLAND.

APPARATUS FOR TIPPING AND DISCHARGING RAILWAY WAGONS.

Application filed February 20, 1925. Serial No. 10,548.

To all whom it may concern:

Be it known that I, FREDERICK GILBERT MITCHELL, a subject of the King of Great Britain and Ireland, residing at Hyde Park, 5 in the county of London, England, have invented Improvements in or Relating to Apparatus for Tipping and Discharging Railway Wagons, of which the following is a specification.

10 This invention has reference to that type of apparatus for tipping and discharging railway wagons which comprises a carrier on to or into which the wagon can be run and which can afterwards be partly rotated 15 to tip the wagon sideways to discharge its contents over one of its sides, the wagon during this operation bearing against one side of the carrier and being held firmly on the rails of the carrier by sustaining means 20 that act upon the wagon in a direction to hold it against the rails.

The present invention has reference to improvements in or relating to wagon tipping apparatus of the kind referred to and it has 25 for its object to simplify the construction and improve the working of such apparatus.

For this purpose, in wagon tipping apparatus according thereto, the carrier comprises wagon supporting means, such as a 30 platform, preferably pivoted, as at one side thereof, (hereinafter called for distinction the near side) to the lower portion of upwardly extending carrying means, conveniently in the form of upwardly extending 35 arms or members to which are fixed a longitudinal laterally arranged wagon supporting member or chock. This member or chock may be at the upper end of the arms and may be journalled at its two opposite ends 40 to the lower arms of a pair of upwardly extending levers that are journalled at intermediate portions of their length to stationary standards or bearings and carry at their upper ends a longitudinal wagon sus- 45 taining beam. Or the arms or members aforesaid may be journalled at intermediate or extended portions of their length to the levers, as may be most convenient. The operating means, which may take various 50 forms, is mounted independently of the carrier, and adapted to tilt the same about its pivotal connection with the levers and the levers about their pivotal connections with the stationary standards or bearings. The

general arrangement of the parts is or may 55 be such that a tilting effort applied to the platform will first cause the latter to move about the lower ends of the carrier arms, until the wagon thereon encounters the lateral supporting member whereupon rotation 60 will take place about the pivotal connection of the latter with the levers until the sustaining beam is encountered by the wagon when the final rotation will be that of the levers about their own stationary 65 bearings.

In the accompanying illustrative drawings, Fig. 1 shows in side view and Fig. 2 in sectional end view, taken on the line II-II of Fig. 1, one construction of wagon 70 tipping and discharging apparatus according to the invention. Fig. 3 is a front view of part of the apparatus showing a modified arrangement. Figs. 4, 5, and 6 are fragmentary end views showing other modifications.

In the example shown in Figs. 1 and 2, a is a wagon supporting platform pivoted at its near side, at a^1 , to lateral extensions b^1 at the lower ends of two pairs of upwardly 80 extending arms or members b . The platform a with its carrying arms and members b is supported, when in its normal and lower position, by bearings c , c^1 conveniently formed respectively by a channel iron bar 85 and masonry arranged below the off and near sides of the platform, d is a longitudinal laterally arranged wagon supporting member or chock, (hereinafter called the lateral support) fixed to the upper ends of 90 the arms b and provided with cushioning devices or fenders d that may conveniently be of rope, e , e are upwardly extending levers journalled at intermediate parts of their length, as by trunnions e^1 , in stationary bearings f carried by standards g arranged at the opposite ends of the lateral support d . To the lower arms of the levers e are pivot- 95 ed, at d^1 , the ends of the lateral support d and to the upper ends of such levers are connected a longitudinal wagon sustaining beam h , carrying bearing blocks h^1 , which may be of cushioning material, to bear against the end walls of a wagon. To the lower arms of each lever e is attached a 100 balance weight e^2 . Upon bearings i , at the near side of the wagon supporting platform a and centrally of the length thereof, is piv- 105

oted, as by means of trunnions j^1 , a member j having a cam-like surface j^2 adapted to receive a flexible connection, as for instance a rope k , which is attached to the said member 5 at a suitable distance from the pivotal connection j^1 for the latter, say at the point m . The flexible connection k is led to a winding drum n driven by a motor, as for example an electric motor o , through reducing gear-10 ing at r . The motion of the cam-like member j is transmitted to the carrier platform a by a strut or pair of struts s that is pivoted at its ends both to the platform a and to the turning member j at s^1 and s^2 respectively. 15 The construction and arrangement of the several movable parts are such that the centre of gravity of such movable parts will, in all working positions of the platform and a wagon thereon, be to that side of a vertical 20 plane passing through the axis e^1 about which the levers e , e turn, that is opposite to that to which the carrier and wagon move when discharging the wagon.

The arrangement is such that when a 25 wagon A is run on to the carrier platform a and the rope k is wound up by the motor driven winding drum n , the platform will, by the turning of the member j , first be caused by the struts s to turn about the pivotal connections a^1 between it and the arms b of the lateral support d , the wagon and platform being thereby slightly tilted and the wagon caused to bear against the said lateral support. Thereafter the platform, 30 wagon and lateral support will move about the pivots at d^1 which connect the said lateral support to the levers e , e , until the end walls of the wagon, at intermediate portions thereof, come into contact with the cushioning blocks h^1 carried by the sustaining beam h . Upon further rotation of the platform a , arms b and lateral support d by the member j , the said levers e , e with all the other associated parts will, as a whole, be caused to 35 turn in the direction of the arrow x about their pivotal connections e^1 with the stationary bearings f , the standards g then supporting nearly the whole of the weight of the moving parts. During the continued 40 moving of the various parts as a whole, to tip the wagon A sideways and discharge its contents, the wagon will be held firmly on the platform a by the sustaining beam h under the action of the weight of the platform a , arms b and lateral support d on the lower arms of the levers e , and a portion of the weight of the wagon itself, assisted by the weights e^2 which, as they are raised, will cause a gradually increasing pressure to be 45 exerted by the sustaining beam on the wagon during the discharge of the wagon.

Upon reversing the direction of motion of the winding drum n , the platform and wagon will, under the action of gravity, 50 be tilted backward and be returned to

their normal lowered position, under the control of the rope k , drum n and motor o .

From this example it will be evident that various modifications may be adopted. For instance, by shortening the lateral support 70 d , or by lengthening the platform a , the arms b may be pivoted to the lower arms of the levers e instead of the lateral support, as shown at b^1 in Fig. 3. Or again, in lieu of using a flexible connection k and winding 75 drum n , the platform a might, as shown in Fig. 4, be connected by a strut or struts s to a toothed quadrant t employed in lieu of the cam shaped member j hereinbefore referred to, the said quadrant being driven by the pinion u of suitable motor operated gearing w^1 . Similarly, in lieu of a strut or struts s pivoted to the platform a and operating cam member j , toothed quadrant t or equivalent, as hereinbefore described, the motion of the latter may, as shown in Fig. 5, be transmitted to the platform a through a sliding connection, such for example as a roller or ball v on one of the parts, say the cam member j , coacting with a curved or appropriately shaped race or seat w on the other part, say the platform a .

The platform a may, as shown in Figs. 1 and 2, be provided with a pair of carrying rails 1 for a wagon A, as heretofore usual, and be supported in its normal lowered position by arranging its underside, or longitudinal girders fixed thereto, to rest upon stationary abutments c and c^1 . Or the off side carrying rail 1 (Figs. 1 and 2) on the wagon platform may, as shown in Fig. 6, be omitted and a rail 1^a be fixed on the ground adjacent to the off side of the said platform. The latter may then be equipped with a near side rail 1 and an off side longitudinal member 4 carried by a pair of arms 5 at a height to engage the underside of the axles 6 of a wagon A initially resting partly on the rail 1 on the carrier and partly on the rail 1^a at the off side of the carrier. A longitudinal guard rail 7 carried by the arms 5 , may be employed to prevent the near wheels of a wagon A leaving the near rail 1 on the carrier a during the raising and tilting operation of the latter. In this case, the platform can be reduced very much in width and the pressure of a strut or struts such as s (Figs. 1 and 2) or equivalent, be applied to the longitudinal member 4 . In all cases, stops may be employed where necessary to resist undesired movement of any of the various parts, and similarly, balance weights may be disposed at and where desired for the purpose of assisting the movement of parts.

The carrier $a-b$ may, as shown in Figs. 1 and 2, be supported above a pit 8 into which the lower end of the cam-shaped operating member j , or equivalent gear may de-

pend, and in which, as shown, may be arranged the winding engine *o* and drum *n* used for operating the apparatus.

What I claim is:—

- 5 1. Apparatus for tipping and discharging railway wagons comprising a wagon support, upwardly extending carrying means for said support, a lateral wagon support connected to the carrying means above the wagon support, stationary bearings, upwardly extending levers pivoted to said bearings and to the lower arms of which the combined carrying means and lateral support are pivoted, a longitudinal wagon sus-
10 taining beam connected to the upper arms of said levers and turning means mounted independently of said wagon support and its carrying means and adapted to act upon and tilt these parts about their pivotal connections with the levers and the levers with their associated parts about the pivots of said levers.
- 15 2. Apparatus for tipping and discharging railway wagons, comprising a wagon support, upwardly extending carrying means to the lower portion of which one side of said wagon support is jointed, a lateral longitudinal wagon support connected to the upper portion of said upwardly extending carrying means, stationary supporting means, a pair of upwardly extending levers pivoted to said stationary supporting means and to the lower arms of which the combined carrying means and lateral support are pivoted, a longitudinal sus-
20 taining beam connected to the upper arms of said levers, additional stationary supporting means, a rotary operating device journalled to the last mentioned supporting means and connected to the pivoted wagon support and motor driven means for causing said rotary operating means to turn about its axis and tilt said wagon support and associated parts substantially in the manner set forth.
- 25 3. Apparatus for tipping and discharging railway wagons, comprising a platform adapted to support a wagon, upwardly extending members having lower lateral extensions to which one side of said wagon support is jointed, a lateral wagon support connected to the upper portions of said members, means for supporting said platform and members in their normal lower positions, stationary bearings at the opposite ends of said lateral support, a pair of upwardly extending levers journalled in said bearings and to the lower arms of which the combined upwardly extending members and lateral support are pivoted, a longitudinal sustaining beam connected to the upper arms of said levers, stationary supporting means arranged to one side and intermediate of the length of said platform, a rotary turning device journalled to said stationary supporting means and connected to the underside of said platform between its ends, and motor driven means for effecting rotation of said rotary device.
- 30 4. Apparatus for tipping and discharging railway wagons, comprising a wagon support, carrying means to which one side of said wagon support is jointed, a lateral wagon support connected to said carrying means, stationary bearings arranged to one side of said wagon support, a pair of upwardly extending levers pivoted to said bearings and to the lower arms of which the combined carrying means and lateral support are pivoted, a longitudinal sustaining beam connected to the upper arms of said levers, rotary operating means mounted to turn about a horizontal axis at a lower level than the axis about which said levers turn and connected to the pivoted wagon support, and motor driven means for actuating and controlling said operating means.
- 35 5. Apparatus for tipping and discharging railway wagons, comprising a wagon support, upwardly extending carrying means to the lower portion of which one side of said wagon support is jointed, a lateral wagon support connected to the upper portion of said carrying means, stationary supporting means, a pair of upwardly extending levers pivoted to said stationary supporting means and to the lower arms of which the combined carrying means and lateral support are pivoted, a longitudinal sus-
40 taining beam connected to the upper arms of said levers, additional stationary supporting means, a rotary operating device journalled to the last mentioned supporting means and connected to the pivoted wagon support and motor driven means for causing said rotary operating means to turn about its axis and tilt said wagon support and associated parts substantially in the manner set forth.
- 45 6. Apparatus according to claim 5, where-
in the rotary turning means is connected to the wagon platform by a strut.
- 50 7. Apparatus for tipping and discharging railway wagons, comprising a platform adapted to support a wagon, upwardly extending members having lower lateral extensions to which one side of said platform is jointed, a lateral wagon support connected to the upper portions of said members, means for supporting said wagon support
- 55 60 65 70 75 80 85 90 95 100 105 110 115 120 125 130

and members in their normal lower positions, stationary supports at the opposite ends of said lateral support, a pair of upwardly extending levers pivoted to said supports and having weighted lower arms, said lateral support being pivotally connected to the lower arms of said levers, a longitudinal sustaining beam connected to the upper arms of said levers, stationary bearings arranged at one side of said wagon support and intermediate of the ends thereof, a rotary device journalled in said bearings and connected to the lower side of said wagon support and motor driven means for turning said rotary device and tilting said platform and associated movable parts alternately in opposite directions about horizontal axes, said platform being arranged above a pit housing the motor driven means and part of said rotary device.

8. Apparatus for tipping and discharging railway wagons comprising a platform adapted to support a wagon, upwardly extending members having lower lateral extensions to which one side of said platform is jointed, a lateral wagon support connected to the upper portions of said members, means for supporting said wagon support and members in their normal lower positions, stationary supports at the opposite ends of said lateral support, a pair of upwardly extending levers pivoted to said supports and having weighted lower arms, said lateral support being pivotally connected to the lower arms of said levers, a longitudinal sustaining beam connected to the upper arms of said levers, stationary bearings arranged at one side of said wagon support and intermediate of the ends thereof, a rotary member pivoted to said stationary bearings, connected to said pivoted wagon support, and having a cam-like surface, a flexible connector secured to said rotary member and extending around the surface thereof, a winding drum for said flexible connector and a motor for driving said drum.

Signed at London, England, this tenth day of February, 1925.

FREDERICK GILBERT MITCHELL.
